**MONOSTABLE MULTIVIBRATOR WITH BIAS
APPLIED TO TAP OF VARIABLE RC NET-
WORK FOR LINEARIZATION OF CHARGE-
TIME**

7 Claims. (Cl. 307—88.5)

This invention relates to a monostable multivibrator and, more particularly, relates to such a multivibrator in which improved circuitry is provided to change the time constant of the state change and thus the duration of the single shot output pulses.

A monostable multivibrator is, of course, known to the art. In such a device, a single input trigger will generate an output pulse, the duration of which is determined by the time constant of an RC circuit coupling the sections of the multivibrator.

In many applications, it is desirable to provide means for changing the timing of the multivibrator and in such applications, the art has provided a variable resistor or potentiometer in the RC timing circuit. By change of the resistance in the timing circuit, the time constant and, thus, the output pulse width of the multivibrator can be changed.

However, in those applications in which a wide variation in timing is desired, certain difficulties are encountered with this type of arrangement. First, when large changes in resistance is necessary, the potentiometer inherently makes it difficult to adjust the timing with the desired resolution over the operating range since the rate of change of resistance per degree of movement of the tap electrode is not a constant in a linear potentiometer (the only practical type for large resistance changes). Secondly, since the RC circuit includes the dropping resistor between the source and the base of one section of the multivibrators, wide variations in resistance will often cause over-driving of the base.

It is, therefore, the primary object of this invention to provide an improved monostable multivibrator in which the effective time constant of the circuit can be changed over a wide range and with high resolution over the entire range.

Other objects and advantages of the invention will be pointed out in the following detailed description which may best be understood by reference to the accompanying figure which is a schematic diagram of a multivibrator constructed in accordance with the present invention.

In the figure, there is shown a multivibrator consisting of transistors 10 and 11, each of which is provided with a base, emitter and collector electrode 14, 16, 18 and 15, 17, 19, respectively. The multivibrator is connected in the usual manner by grounding the emitter electrodes 16 and 17. The collector electrode 19 is coupled to source 20 through resistor 22 and is tied back to the base electrode 14 through resistor 24 which may be bypassed by capacitor 26. The collector electrode 18 is coupled through circuit 28 and the timing capacitor 30 to the base electrode 15 of transistor 11. The base electrode 15 is coupled through resistor 32 to terminal 34. A potentiometer 36 is provided, the end terminals being coupled between terminals 34 and 38 and the tap electrode 40 thereof being coupled to source 20. Resistor 42 is provided between junction 38 and ground. Terminal 38 is also coupled through circuit 44 and the collector resistor 46 to the collector 18 of the transistor 10. A positive supply voltage source 21 is connected through resistor 48.

The circuit 28 is merely an emitter follower comprising

2

a transistor 50 coupled to an emitter follower circuit to make the junction 52 a low impedance point. Similarly, circuit 44 is an emitter follower to make junction 38 a low impedance point. Aside from the problems of impedance matching, these circuits should be omitted. For example, circuit 28 is conventionally included in this point to make point 52 a low impedance point thereby to improve the recovery characteristics and recovery speed of the circuit without, however, influencing the circuit operation in other aspects.

In operation, the transistor 10 is cut off and transistor 11 is saturated. An input pulse as, for example, applied over lead 54 would be a negative-going pulse to bring the base 14 of transistor 10 negatively starting conduction of transistor 10. As a result, junction 52 will go positively swinging base 16 positively to decrease the conduction in transistor 11, in turn swinging collector 19 negatively to further increase the current of transistor 10. As is well known, this swing is very fast and the circuit reaches a stable point with transistor 10 conducting. Conduction is continued during the discharge of the timing capacitor 30 through resistor 32 and the portion of potentiometer 36 between the tap 40 and terminal 34. Thus, the tap position varies the R of the timing circuit.

As the timing capacitor 30 discharges through the resistors 32 and the portion 36 and the low saturation resistance of the conducting transistor 10, the base 15 of transistor 11 becomes less positive. When the base potential becomes slightly negative, transistor 11 again conducts. The collector potential 19 increases positively and since this potential is coupled to the base 14 of transistor 10, drives transistor 10 to cut off. Thus, transistor 10 will again be cut off and transistor 11 will conduct in saturation with its collector voltage substantially at zero. This stable condition is maintained until another pulse triggers the circuit.

The adjustment of the timing by movement of the tap 40 on potentiometer 36 is the result of two effects. The first effect of tap movement is variation in the resistance serially connected to the timing capacitor. This variation of tap position changes the RC time constant of the timing circuit with concomitant changes in the duration of the output pulse. The second effect of movement of tap position is variation of the voltage applied across the collector resistor 46, thus, varying the swing of potential across the resistor 12 by the drop through the potentiometer resistance between the tap position 40 and terminal 38 thereof.

For example, if the tap 40 is moved to terminal 34 at the extreme end of the potential, the time constant of the timing circuit will be the lowest since the resistance is the lowest. Simultaneously, the voltage across resistor 46 is the lowest and the width of the pulse output as indicated by wave form 56 derived from the collector of transistor 11 by lead 58 will be the shortest.

If, on the other hand, the tap is moved to the extreme end of potentiometer 36 by movement to terminal 38, the maximum resistance will be introduced into the timing circuit and at the same time, the highest voltage will be applied across collector resistor 46 to give the highest voltage swing thereacross and the lowest time of the pulse output.

The combination of the two effects linearizes the potentiometer so that the rate of change of time bears a substantially linear relationship to the rate of change of movement of the tap position.

By way of complete disclosure, but not by way of limitation, the component values listed in Table I are typical of an operating circuit constructed in accordance with the present invention.

Table I

Component Number	Component Identification	Value
10	Transistor	2N1309.
11	do	2N1309.
50	do	2N1309.
60	do	2N1309.
62	Diode	G272.
63	do	G272.
20	Supply	-15 volts. +15 volts.
21	do	10K.
36	Potentiometer	1K.
46	Resistor	100 ohms.
64	do	3K.
66	do	100 ohms.
68	do	3.9K.
42	do	15K.
49	do	68K.
32	do	7.5K.
48	do	1K.
24	Capacitor	2000 pF.
22	do	100 pF.
30	do	1 microfarad.
26	do	Do.
27	do	
28	do	

This invention may be variously modified and embodied within the scope of the subjoined claims.

What is claimed is:

1. A monostable multivibrator having, a first and second transistor, each of said transistors having at least a base, collector and emitter electrodes, a timing capacitor coupling the collector electrode of said first transistor to the base electrode of said second transistor, a biasing source, a potentiometer having a first and second terminal and a tap electrode adjustably positioned between said first and second terminal, means coupling said biasing source to said tap electrode, a first resistor coupling said base electrode of said second transistor to said first terminal of said potentiometer, a second resistor coupling said collector electrode of said first transistor to said second terminal of said potentiometer, a third resistor coupling said second terminal of said potentiometer to ground, whereby movement of said tap electrode simultaneously changes the effective resistance in the timing circuit including said timing capacitor and changes the potential applied to the collector electrode of said first transistor.
2. A monostable multivibrator in accordance with claim 1 which includes an emitter follower coupled between the collector electrode of first transistor and said timing capacitor to improve the recovery speed of the multivibrator.
3. A monostable multivibrator in accordance with claim 1 which includes an emitter follower coupled between said second resistor and said second terminal of said potentiometer to make said second terminal a low impedance point in said circuit.
4. A monostable multivibrator in accordance with claim 1 in which said transistors are PNP type transistors and in which said source is a source of negative voltage.
5. A monostable multivibrator having an adjustable timing of the output pulse therefrom, which comprises, a first and second transistor,

- 4
- each of said transistors having a base, collector and emitter electrodes, means coupling said base electrodes of said first and second transistors to ground, a first resistor coupling said base electrode of said first transistor to said collector electrode of said second transistor, a capacitor coupled across said first resistor, a timing capacitor coupling said collector electrode of said first transistor to the base electrode of said second transistor, a bias source, a potentiometer having first and second terminals and a tap electrode adjustably positioned between said first and second terminals, means coupling said bias source to said tap electrode, a first collector resistor coupling the collector of said first transistor to said second terminal of said potentiometer, a second collector resistor coupling the collector electrode of said second transistor to said bias source, a timing resistor coupling said base electrode of said second transistor to said first terminal of said potentiometer, resistor means coupling said second terminal of said potentiometer to ground, a second bias source of opposite polarity and resistor means coupling said second source to the base electrode of said first transistor, whereby movement of said tap electrode will vary the time of the output of said multivibrator linearly with movement of said tap electrode.
6. A monostable multivibrator in accordance with claim 5 which includes, a third transistor having a base, emitter and collector electrodes, a third collector resistor coupling the collector electrode thereof to said bias source, an emitter resistor coupling said emitter electrode of said third transistor to ground, means coupling said first collector resistor to the emitter electrode of said third transistor, and means coupling said base electrode of said third transistor to said second terminal of said potentiometer.
  7. A monostable multivibrator in accordance with claim 5 which includes, a fourth transistor having a base, collector and emitter electrodes, a fourth collector resistor coupling said collector electrodes to said bias source, a second emitter resistor coupling said emitter electrode of said fourth transistor to said second bias source, means coupling said emitter electrode to said timing capacitor, means coupling said base electrode to the collector electrode of said first transistor, and a diode, said diode being coupled between said base and emitter electrodes of said fourth transistor.
